US0D1066729S

(12) **United States Design Patent** (10) **Patent No.:** **US D1,066,729 S**
(45) **Date of Patent:** **** Mar. 11, 2025**

(54) **COLLECTION DEVICE**

- (71) Applicant: **Becton, Dickinson and Company**, Franklin Lakes, NJ (US)
- (72) Inventors: **Weston F. Harding**, Lehi, UT (US); **Austin Jason Mckinnon**, Herriman, UT (US); **Matthew Oshinski**, Oak Ridge, NJ (US)
- (73) Assignee: **Becton, Dickinson and Company**, Franklin Lakes, NJ (US)
- (**) Term: **15 Years**
- (21) Appl. No.: **29/870,291**
- (22) Filed: **Jan. 20, 2023**

Related U.S. Application Data

- (62) Division of application No. 29/795,837, filed on Jun. 21, 2021, now Pat. No. Des. 976,437, which is a (Continued)

(57) **CLAIM**

The ornamental design for a collection device, as shown and described.

DESCRIPTION

FIG. 1 is a top, back, and right perspective view of a vial of a collection device, showing our new design; FIG. 2 is a top, back, and left perspective view thereof; FIG. 3 is a back elevation view thereof; FIG. 4 is a front elevation view thereof; FIG. 5 is a right side elevation view thereof; FIG. 6 is a left side elevation view thereof; FIG. 7 is a top plan view thereof; FIG. 8 is a bottom plan view thereof; FIG. 9 is a bottom, back, and right perspective view thereof; FIG. 10 is a bottom, back, and left perspective view thereof; FIG. 11 is a cross-sectional elevation view taken along line 11-11 shown in FIG. 7; and, FIG. 12 is a cross-sectional plan view taken along line 12-12 shown in FIG. 3.

The broken lines illustrate portions of the vial of the collection device which form no part of the claimed design. The dot-dash lines illustrate boundary lines between claimed and unclaimed regions of the collection device and form no part of the claimed design.

1 Claim, 8 Drawing Sheets

Related U.S. Application Data

division of application No. 29/704,831, filed on Sep. 6, 2019, now Pat. No. Des. 923,195, which is a division of application No. 29/618,544, filed on Sep. 21, 2017, now Pat. No. Des. 859,683.
